AUTOMATIC WEFT REPLENISHING DEVICE

Juan Picañol Camps, Sabadell, Spain

Application September 3, 1932, Serial No. 631,630
In Switzerland June 21, 1932

2 Claims. (Cl. 139—250)

This invention relates to an automatic weft replenishing device for looms for weaving of the type in which the weft carrier is in the form of a rotary drum such as the Northrop type of rotary drum.

According to the present improvements, the automatic weft replenishing device is characterized in that the drum which carries the weft carriers or bobbins is made to advance, for the purpose of ensuring that the flyers, which guide the bobbins, remain parallel to the lateral sides of the shuttle, from the commencement of the transfer, until the end of its movement which is synchronous with the horizontal component of the hammer, thus producing a completely vertical change or straight movement of weft carriers or bobbins from the drum to the shuttle. The circular path of the end of the hammer during transfer movement is such that the change can be effected during an advancing movement of 18 to 25 mms., or more, of the sley of the loom. In addition to the movement of the drum during the transfer, a movement is given to the drum to place the next succeeding weft carrier or bobbin under the transfer hammer ready for the next transfer.

The attached drawings form an integral part of this specification, and show by way of example, a convenient embodiment of the invention.

Figure 1 is a side view of the device.

Figure 2 is a front view of the same, partly in section.

A drum 13 provided with radial flyers 19 has a toothed ring 14 with outwardly projecting notch-shaped teeth and a toothed ring 3 with inwardly projecting ratchet teeth. One end of a pawl 4 engages the ring 3, the other end of this pawl being pivotally mounted on a stud 18 fixed in a lug 7b on a rocking lever 7 mounted on a spindle 8 by means of a second lug 7a. A hammer 1 in the form of an elbow lever and comprising two arms 1a and 1b is oscillatable around a spindle 10 and normally maintained in raised or inoperative position by a spring 20. The arm 1b of this elbow lever is also mounted on the spindle 8. A lever 9 is pivotally mounted on the spindle 8 and has at its end a catch head 21 which is resiliently maintained in engagement with the toothed ring 14 by means of a spring 2. The lever 7 also carries a tappet roller 5 adapted to bear against the under side of the lever 9 and press the catch head 21 in engagement with the toothed ring 14. A pin 11 is fixed on the lever 7 and engages in the forked end of

a lever 12 mounted on a spindle 15. A catch 17 is provided on the end of the lever 7, which catch engages a stop 16 fixed on the sley of the loom.

The device operates in the following manner:

When it is desired to transfer a bobbin from the drum 13, the spindle 15 is rocked in any suitable manner. This movement is imparted by the lever 12 and pin 11 to the rocking lever 7, which consequently swings into horizontal position so that the roller 5 bears against the under side of the lever 9 and presses the catch head tightly into engagement with the ring 14, thereby locking the drum against rotation. During this movement the pawl 4 mounted on the stud 18 is advanced over the toothed ring 3. When the lever 7 is in horizontal position, its catch 17 is in the path of movement of the stop 16 fixed on the sley and this stop engages in the catch 17 when the sley has still 18 to 25 mms. to travel before reaching the end of the beat up movement. Consequently the lever is displaced 18 to 25 mms. by the sley. Owing to this displacement the spindle 8 is also displaced causing the hammer to swing about its spindle 10 and press the bobbin out of the flyer 19 into the sley.

As the lever 9 is also mounted on the spindle 8, it will likewise be displaced and its catch head 21 will rotate the drum 13 so that the bobbin is gradually brought into the delivering position during the transfer so that a straight movement of the bobbin from the drum to the shuttle takes place during the transfer.

When the sley commences its return movement, the lever 7 is liberated and parts are returned into their initial positions by the spring 20. The lever 7 is then swung downwards by means of the lever 12 and spindle 15 so that the roller 5 is removed from the underside of the lever 9, thereby releasing the lever so that it is held in engagement with the ring 14 merely by its spring 2. Owing to this downward movement of the lever 7 a pull is exerted on the pawl 4 which consequently rotates the drum. During this rotation the catch head slides into the next following gap in the ring 14 against the action of the spring 2.

What I claim is:

- An automatic weft replenishing device comprising in combination with the sley of the loom, a stop on said sley, a spindle adapted to be rotated to bring the device into action, a forked lever keyed on said spindle, a rocking lever carrying a roller engaging in the forked end of said lever and having a catch at its end adapted to

be brought into horizontal position in front of said stop, a drum over said slay provided with radial flyers, an internally toothed rim on said drum, a pawl engaging said rim and cooperating 5 with said rocking lever to rotate said drum at the end of the movement of said slay after said stop has engaged said catch, a spring loaded lever adapted to engage in said rim to lock said drum during the replenishing action, a roller on said 10 rocking lever adapted to hold said spring loaded lever in engagement with said rim when said rocking lever is in horizontal position and a hammer pivotally mounted on said rocking lever adapted to shift horizontally during the transfer

to produce a straight movement of the bobbin from the drum to the shuttle.

2. An automatic weft replenishing device, as set forth in claim 1, characterized in that, in the application of the automatic weft replenishment 5 to the Northrop type of rotary drum, means are provided to effect the change compatible with a very long travel of the sley of the loom, whereby in addition to the movement of the drum during the transfer a movement is given to the drum to 10 place the next succeeding weft carrier or bobbin under the transfer hammer ready for the next transfer.
